TRANSFORMER

Arni Helgason, Wilmette, Ill., assignor to Chicago
Transformer Corporation, Chicago, Ill., a cor-
poration of Illinois

Application May 28, 1934, Serial No. 727,842

7 Claims. (Cl. 175—361)

This invention relates to transformers and particularly to small transformers having all the leads thereof coming out of one end. Transformers of this type, such as, for example, power supply transformers for radio receivers are usually mounted vertically on a chassis pan. A suitable aperture is stamped out of the pan and a portion of the transformer including the wiring leads extends below the top of the chassis 5 pan and into the interior thereof. The transformer is bolted in this fashion and usually presents a clean exterior unbroken by any wiring.

In the case of radio receivers—and, in fact, in any electrical device employing transformers—the occasion frequently arises when the transformer ratio must be varied. While 110 volts, 60 cycles is the usual standard in this country, there are numerous and varied voltages in other 10 parts of the world. In a case of this character, particularly where it is desired to export radio receivers or other articles employing a transformer, it is desirable from a production standpoint to employ a universal type of transformer 15 which may be mounted in the apparatus and connected in the usual manner. In the event that the transformer ratio must be changed to take care of different voltages, it is desirable that some simple method be available for accomplishing the above. In order to avoid service difficulties, and in order to make it possible for a lay-man to accomplish this, it is necessary that this method be simple and fool-proof. Furthermore, it is necessary that this method be economical. In addition, it is desirable that the 20 change be effected from the exterior of the aperture rather than from any interior portion thereof. In the case of a radio receiver, the maze of wiring in the chassis pan is such as to preclude the possibility of a fool-proof and effective change. Furthermore, by making it possible to make the change from the exterior of the apparatus, it is evident that just prior to final checking, when the radio receivers or other 25 devices are stacked, a person can simply go over the various units and make the necessary changes without turning over of any of the units.

Referring to the drawing, Figure 1 is an illustration of a transformer employing this invention. Figure 2 is a plan view looking down upon this same transformer. Figure 3 is a circuit diagram of the transformer.

Referring to the drawing, a pair of pressed steel end shields or bells 1 and 2 are shown. 30 Between these is a stack of laminations 3 en-

closing a plurality of windings. The transformer is mounted upon a suitable base 5. The transformer laminations are clamped together and the entire transformer structure is supported on base 5 by means of bolts 10 and nuts 11. The windings of the transformer have a plurality of leads 12 to 20 inclusive, for outside connection, projecting through suitable apertures in the bottom of bell 2.

As shown in Figure 3 the transformer windings 10 comprise a primary 25 and a secondary 25'. Primary 25 has a plurality of taps 26 to 29 inclusive, and also, end connections 12 and 30. These wires 26 to 30 inclusive are all taken out through the top end of the transformer through 15 bell 1. Supported by bell 1 and in spaced relation thereto is an insulating pan 31 of bakelite or similar material, having a plurality of binding posts 36 to 40 inclusive. To each post leads 26 to 30 inclusive, are respectively connected. 20 A connector lead 13 from the bottom end of the transformer is carried through the transformer to the top thereof and terminates in a connecting lug 41. The entire top may be protected by a metal cover 45 maintained in place by any 25 well known means.

It is evident that the various leads 12 to 20 inclusive of the transformer projecting below base 5 may be permanently wired to utilization circuits on the production line in the customary 30 manner. Thereafter in the event that any particular voltage is desired such as, for example, the voltages shown adjacent the binding posts 36 to 40 inclusive, the corresponding nuts on these binding posts may be loosened and lug 35 41 of lead 13 may be connected to any desired post. It is obvious that this connection may be made by any unskilled person in an exceedingly short time and does not require any tools or elaborate equipment. It is also obvious that the 40 secondary winding may be operated upon in this manner rather than the primary or even both windings. All leads for connection to an external circuit are led out on one side of the transformer and all leads including at least one jumper from the external circuit leads are brought out from a different side of the transformer for internal circuit connection.

What is claimed is:

1. A transformer comprising laminations and 50 windings each winding having at least two terminal leads and at least one winding having a plurality of intermediate tap leads, said tap leads and one terminal lead of the corresponding winding out of said transformer being 55

brought out on one side thereof, said leads being provided with binding terminals, the remaining leads of said transformer being brought out from another side thereof, said other leads being 5 adapted to be permanently connected to external circuits, and a connector lead going through said transformer from one side to the other and having one end for ready connection with any one of said binding terminals and the other end with said remaining leads for permanent connection with an external circuit.

2. A transformer comprising a stack of laminations, a plurality of windings having terminal leads and at least one winding having a plurality 10 of tap leads, end plates for said transformer, said tap leads and one of the terminal leads passing through one of said end plates for internal circuit connection, the remaining leads passing through the other end plate for external 15 circuit connection, said transformer being adapted to be mounted on a base with the end plate and external circuit leads extending below said base plate and a connector lead extending through the transformer from one end plate 20 through the other and having ends extending therethrough, said connector lead being adapted to be connected to any one of said internal circuit group of leads for altering the transformer ratio.

3. The structure of claim 2 wherein the internal circuit leads are brought up to a terminal board whereby the corresponding connector lead end may be readily connected to any desired lead.

4. A transformer comprising a stack of laminations, a plurality of windings in transformer relationship therewith and including at least one primary and secondary, terminal leads for said primary and secondary windings, intermediate 30 tap leads for at least one of said windings, said one winding having one terminal lead and all tap leads extending in one direction from one side of said transformer, said other winding having all its connections extending in another direction from

another side of said transformer, the remaining terminal lead of said one winding also extending from the same direction and transformer side as the connections from the other winding, said transformer being adapted to be mounted in such a fashion as to make access to said other side of said transformer and the connections coming out therefrom difficult while said one side of said transformer and the leads coming therefrom are readily accessible, and a connector lead passing 35 through said transformer structure having one end extending from said one direction from said one side of said transformer and its other end extending from said other direction and side of said transformer, whereby said first end of said connector may be readily connected to any desired tap lead to alter the transformer ratio without moving the transformer from its mounting.

5. The transformer of claim 4 wherein all the leads coming from said other side of said transformer are adapted to be permanently connected in suitable circuits while the leads coming from said one side of said transformer are provided with means for making detachable connections.

6. The transformer of claim 4 wherein all the leads coming from said other side of said transformer are adapted to be permanently connected in suitable circuits while the leads coming from said one transformer side are connected to a terminal board whereby any desired connection to alter the transformer ratio may be readily established.

7. The transformer of claim 4 wherein all the leads coming from said other side of said transformer are adapted to be permanently connected in suitable circuits and a terminal board is carried by said transformer on its one side to which is connected the one terminal and tap leads extending from said one side of said transformer while said connector lead is adapted to be readily connected to any desired terminal of said board to alter the transformer ratio.
